(57) **CLAIM**

The ornamental design for a mobile phone holder with speaker, as shown and described.

DESCRIPTION

FIG. 1 is a front, right and top perspective view of a mobile phone holder with speaker, showing my new design;

FIG. 2 is a rear, left and bottom perspective view thereof; FIG. 3 is a front, right, and top perspective view of the article shown in a folded state;

FIG. 4 is a front view of the article as shown in FIG. 1;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the mobile phone holder with speaker that form no part of the claimed design.

1 Claim, 9 Drawing Sheets
